UNITED STATES PATENT OFFICE.

FRANK G. DELBON, OF BROOKLYN, NEW YORK, ASSIGNOR TO WILLIAM LANE INC., OF BROOKLYN, NEW YORK, A CORPORATION OF NEW YORK.

SHOE.

1,161,930.

Specification of Letters Patent. Patented Nov. 30, 1915.

Application filed March 8, 1915. Serial No. 12,808.

To all whom it may concern:

Be it known that I, FRANK G. DELBON, a citizen of the United States, and a resident of Brooklyn, in the county of Kings and 5 State of New York, have invented certain new and useful Improvements in Shoes, of which the following is a specification.

The invention pertains more particularly to low shoes to be worn by ladies and variously designated, the main object of the invention being to provide a shoe of this character having the appearance of being either laced or buttoned, while in reality the lacing and buttoning effects are of permanent 15 character and not intended for hand manipulation.

The invention comprises, therefore, the formation at the upper front portion of the shoe of such features as will impart to the shoe the effect of being either laced or buttoned and in having at the back of such portions of the shoe a permanent portion of the lining of the upper of the shoe.

The invention will be fully understood 25 from the detailed description hereinafter presented, reference being had to the accompanying drawings, in which:

Figure 1 is a perspective view of a shoe constructed in accordance with and embodying my invention, the shoe in this instance being equipped with lacing features of permanent character; Fig. 2 is a corresponding view of another form of shoe, the shoe in this instance having features imparting a buttoned effect thereto; Fig. 3 is a side elevation, partly broken away and partly in section, of the shoe illustrated in Fig. 1, and Fig. 4 is a section on a still larger scale 35 through the upper front portion of the shoe 40 illustrated in Figs. 1 and 3.

In the drawings, referring to Figs. 1, 3 and 4, 10 designates the shoe as a whole having an upper portion preferably formed of two different kinds of material, as, for 45 instance, patent leather for the part 11 and cloth or kid for the part 12. At the upper front portion of the shoe the leather of the part 11 extends upwardly to form a permanent tongue 13, and the material of the part 50 12 extends upon said tongue from opposite edges thereof forming imitation flaps or edge portions 14 lapping upon the tongue 13 and preferably bound by strong silk or the like 15, this binding being continued en-

tirely around the upper edges of the shoe 55 section 12.

Upon the forwardly projecting or flap sections 14 are preferably secured by sewing lengthwise strips 16 of patent leather or other material, and in these strips 16 and 60 the adjacent portions of the shoe exterior to the lining 17 thereof, are eyelet holes 18 through which a lace 19 is threaded, the ends of the lace being brought together and tied adjacent to the upper edges of the flaps 14. 65 The lace 19 is exterior to the lining 17, as I illustrate in Figs. 3 and 4, and said lace is permanently applied to the shoe and serves no special function other than to impart to the shoe the effect of the shoe being a 70 laced shoe. The shoe constructed as shown in Figs. 1, 3 and 4 not only possesses the merit of imitating a laced shoe, but also of having its particular artistic form permanently set, all of the parts of the shoe being firmly fastened together and the lining 75 17 by being continuous across the front of the shoe, holding the shoe upper in its permanent and proper form or shape. The lining 17 also keeps the lace 19 from contact with the stocking.

In respect to Figs. 1, 3 and 4 the shoe illustrated therein possesses therefore the appearance of a laced shoe although in reality not a laced shoe but one having an inner 85 unbroken or continuous front and outer permanently applied parts representing flaps laced together across the tongue 13 which is also permanently located.

In Fig. 2 I illustrate a shoe embodying 90 many features of the invention but, as distinguished from Fig. 1, having the effect of a buttoned shoe. In Fig. 2 20 designates the shoe as a whole having an upper formed of sections 21, 22, the section 21 being of 95 suitable material, as, for example, patent leather, while the section 22 may appropriately be formed of white kid or of other suitable material.

The side portions of the section 22 extend 100 forwardly on gradually converging lines, as at 23, and one of said portions terminates, as at 24, at one side of the longitudinal center of the shoe upper, while the forward part of the other side portion crosses over 105 the front of the shoe and has a buttonhole 25 engaged with a button 26 which is on the portion 24. That portion of the section 22

which extends over the front of the shoe may be termed a strap or tongue 27, and it will preferably have a binding 28 of silk or the like, said binding being continued 5 entirely along the upper edge of the section 22. The tongue 27 may be variously shaped, and in the drawings it is shown as projected upwardly, as at 29, at the longitudinal center of the shoe and serving the purpose of 10 a tongue, such as 13 shown in Fig. 1. The shoe shown in Fig. 2 is of the same permanent character as the shoe shown in Fig. 1, the tongue 27 being sewed down to the inner adjacent portions of the shoe as well as to 15 the section 21 and that portion of the section 22 overlapped by it. The lining 30 of the shoe 20 continues without break along the upper front portion of the shoe correspondingly with the lining 17 of Figs. 1, 3 and 4. 20 The upper front portion of the shoe 20 is, therefore, of permanent character and will retain the predetermined shape given to it. The tongue 27 and button 26 impart an ornamental character to the shoe and convey 25 the impression of a buttoned shoe, whereas in fact the shoe cannot be opened at the upper front portion but on the contrary remains permanently closed thereat.

My invention admits of various forms of 30 ornamental front effects being imparted to the shoes as, for instance, the tongue 27 might extend straight across the upper front portion of the section 21 and a part of the section 21 might be extended upwardly below 35 said tongue to create a conventional tongue, as 13, in Fig. 1. I do not desire to limit myself, therefore, to the exact details illustrated.

What I claim as my invention and desire 40 to secure by Letters Patent, is:

1. A low cut shoe whose upper is in two sections, one section extending above the other at the front portion of the shoe, the upper section at the front portion of the

shoe having a permanent continuous lining 45 and exteriorly being cut to imitate a shoe having opening and closing parts and said parts being sewed down and also equipped with conventional fastening-means.

2. A low cut shoe whose upper is in two 50 sections of contrasting materials, one section extending above the other at the front portion of the shoe, the upper section at the front portion of the shoe having a permanent continuous lining and exteriorly being 55 cut to imitate a shoe having opening and closing parts and said parts being sewed down and also equipped with conventional fastening-means.

3. A low cut shoe whose upper is in two 60 sections, one section extending above the other at the front portion of the shoe, the upper section at the front portion of the shoe having a permanent continuous lining and exteriorly being cut to imitate a shoe 65 having opening and closing eyeleted parts and said parts being sewed down and also equipped with a lace threaded through said eyelets exterior to said lining.

4. A low cut shoe whose upper is in two 70 sections, one section extending above the other at the front portion of the shoe, the upper section at the front portion of the shoe having a permanent continuous lining and exteriorly being cut to imitate a shoe 75 having opening and closing eyeleted parts and said parts being sewed down and also equipped with a lace threaded through said eyelets exterior to said lining, and the lower of said two sections having a front tongue 80 between said eyeleted parts and lining.

Signed at New York, in the county of New York and State of New York, this 23rd day of February, A. D. 1915.

FRANK G. DELBON.
